Primary Examiner — Nicole C Shiflet*Assistant Examiner* — Danielle Nichole Bowly(57) **CLAIM**

The ornamental design for a desk calendar, as shown and described.

DESCRIPTION

FIG. 1 is a top, right and front side perspective view of a desk calendar, showing my new design;
 FIG. 2 is bottom, right and back side perspective view thereof;

FIG. 3 is a front elevational view thereof;

FIG. 4 is a back elevational view thereof;

FIG. 5 is a left side elevational view thereof;

FIG. 6 is a right side elevational view thereof; and,

FIG. 7 is a top plan view thereof.

The broken lines shown in the drawings illustrate portions of the desk calendar that form no part of the claimed design.

1 Claim, 7 Drawing Sheets(56)
